FIG. 5. Geo. C. Avery

BY
J. N. McDermott
ATTORNEY

UNITED STATES PATENT OFFICE.

GEORGE C. AVERY, OF LOUISVILLE, KENTUCKY.

MOLDING-MACHINE.

SPECIFICATION forming part of Letters Patent No. 507,577, dated October 31, 1893.

Application filed November 25, 1892. Serial No. 453,007. (No model.)

To all whom it may concern:

Be it known that I, GEORGE C. AVERY, of Louisville, in the county of Jefferson and State of Kentucky, have invented a certain new and useful Improvement in Molding-Machines; and I do hereby declare that the following is a full, clear, and exact description of the same, reference being had to the accompanying drawings, forming part of this specification.

10 My invention relates to machines for making molds in sand, or other material, and such as are used generally for the molding, or casting, of articles in metal.

15 Previous to my invention machines have been made by the use of which, after a sufficient quantity of sand, or other suitable material, had been placed in a receptacle, and a pattern arranged in contact with and partially surrounded by the sand, the latter was 20 subjected to pressure, to compress and solidify the mass, and so as to perfect the impression in the mass of sand of the pattern of the article to be subsequently cast in said mold; but I propose to provide for use a machine 25 radically different, in principle of construction and mode of operation, from any heretofore devised, and one which shall be capable of more efficient, rapid, and easy use, than any heretofore made that I know of.

30 To this main end and object my invention consists in a molding machine comprising the novel characteristic features and combinations of devices which will be found herein-after more fully described, and that will be 35 found most particularly pointed out in the claims of this specification.

To enable those skilled in the art to which my invention relates, to make and use molding machines containing, either partially, or 40 wholly, my said improvements, I, will now proceed to more fully describe the latter, referring by letters to the accompanying drawings, which form part of this specification, and in which I have shown my invention carried 45 into effect in that form of machine in which I have, so far, practiced it, though modifications therein may be made without departing from the spirit of my said invention.

In the drawings, Figure 1 is a side view, or 50 elevation of a machine fully embodying my invention. Fig. 2, is an end view of the same, looking at the machine in the direction indicated by the arrow 2, at Fig. 1. Fig. 3, is a vertical cross section at the line x, x, of Fig.

1, looking in the direction of the arrow marked 55 3. Fig. 4, is a vertical longitudinal partial section at the line y, y, of Fig. 2, and Fig. 5 is a detail view, showing, in perspective, and detached from the rest of the machine, a modified form of mold-supporting plate, or device. 60

In the several figures the same part will be found always designated by the same letter of reference.

A, is the body, or main-frame of the machine, which, as shown, is cast with two upwardly projecting stand-like portions B, B (one at each end), each of which has a square perforation through it, to accommodate one of the two square plunger-rods, or piston-rods, b, b², which are arranged to slide longitudinally in said perforations, and in the same line axially. Said body-portion, or main casting A, is also formed with a horizontal plate-like portion a, the upper surface of which forms, essentially, the sand, and mold-supporting plane; and with depending ear-like parts f, f, one at each end and lower portion of the casting, which ears f, f are bifurcated, or slotted out, to accommodate the angular portions of two bell-cranks, or bent levers, G, G, that are pivotally hung therein. The inner ends of the piston rods b, b², are provided, respectively, with plungers, or pistons D and E, which are of about the same size, and which, in the case shown, are square in contour, and 75 patterned, or shaped, much after the pattern of a press; while the outer ends of said rods b and b², are slotted out, and are pivotally connected, respectively, with the upper ends of the vertical arms of the bent levers G, G. 80 In the case shown, the pivotal connections, or couplings, between said piston rods and the upper ends of said bent levers, comprise the pins g, g, arranged horizontally in the slotted ends of the rods b, b², and transversely of their 85 slots, and oblong apertures e, in the ends of the bent levers, through which said pins pass. 90

h, h, are the pivotal pins which pass through the ear-pieces f, f, and through the body-portions of the bent levers G, G, for the latter to turn on, and the adjacent ends i, i of said levers are supposed to be connected with and operated by a toggle-joint, or other suitable mechanism, to which power is applied at the pleasure, or option, of the attendant of the 100 machine, to effectuate the necessary up and down movement of these ends i, i, for the performance (as will be presently explained) of 105

the said compressing operation in making the mold.

C is a sort of sliding frame, or receptacle, which, for about one-half of its length, comprises only two vertical walls, or side-plates, (which are just far enough apart to permit the entrance and passage between them, of the plungers, or pattern-like devices D and E,) and which, during the other half of its length, comprises the said vertical walls, and also a top-plate l, preferably cast integral with the said side-plates. The lower, parallel, edges of the side walls of said frame-like device C, are enlarged and formed, in the case shown, with a sort of dovetailing feet, which are accommodated within, and slide freely in correspondingly shaped grooves, or channels, cut in the horizontal, plate-like portions a, a, of the main casting (see Figs. 2 and 3); all as clearly shown in the drawings.

Preferably, plates, or shoe-pieces m, are arranged intermediate of the tapering surfaces of the lower edges of the frame C, and the tapering, or beveled, surfaces of the channels cut in the casting a; which shoe-pieces, or wear-plates, are backed up by a series of set screws n, by means of which the plates can be adjusted, and the longitudinally sliding, lower, edges of frame C kept in fit, or in perfect working condition, in the ways, or channels, in which they move. The side-plates of the device C are provided exteriorly, and in the case shown, at about their middle portions, with bosses o, o, in which are fitted trunnions, or outwardly projecting pins, to which are pivotally coupled one set of ends of the two link bars I, I, the other ends of which are coupled, as clearly shown, to the upper ends of a pair of vertically arranged arms J, J, which, at their lower ends are keyed fast to a rock-shaft M. The said shaft is journaled, near each end, in the depending ear-pieces N, M (see Fig. 2) of the main casting, or body of the machine, and keyed fast on said rock-shaft M, is a hand lever F (see Figs. 1 and 2), by means of which said shaft may be oscillated at pleasure, to effectuate the sliding of the frame C, as will be presently described.

H is a plate, which, as shown, is arranged in a transverse depression, or recess, formed in the top surface of the portion a of the main casting, and which rests on six (more or less) set screws s, which are tapped into the plate-like part a of said casting, and the ends of which protrude upward through said casting, at the vicinity of the recess, or depression, within which said plate H is located. Preferably, these set screws s are of hardened steel, so that their ends, which contact with and support the plate H will be very durable, and, by preference, the said plate is provided with a series of metallic buttons, or button-like projections z, (see Figs. 1 and 5,) which serve a special purpose to be presently explained.

In the machine shown, at Figs. 1 to 4, in-

clusive, the device H is a simple flat narrow plate, while at Fig. 5 is shown a modification of this device, in which the plate H is supplemented with vertical upwardly projecting pieces H², and a top brace, or tie-rod w, which lies parallel with the bottom plate of the device, and serves to connect and hold together securely, the vertical walls H² of the device.

The machine shown and so far described and mainly, with reference to the construction and arrangement together of its parts, operates, or is worked, in the following manner: Supposing the movable parts to be set in, or adjusted to, about the positions, or condition, illustrated in the drawings (see particularly Figs. 1 and 4), and supposing any desired pattern, or patterns, (to be molded) to be secured in place on the face, or faces, of one, or both, of the plungers D, E, the attendant, or operator, of the machine fills in, with sand, the space bounded on two opposite sides by the side walls of the frame C, and on two other opposite sides by the faces of the plungers D and E (with their attached and inwardly projecting patterns); the sand, or other material for forming the mold resting, of course, on the top surface of the plate-like portion a of the main casting of the machine, and, incidentally, also on top of the plate H. After having thus properly packed the said space, or receptacle, with the molder's sand, the operator then lifts the handle, or free end of lever F, and thus turns the rock-shaft, with its upwardly projecting, fast, arms J, J, sufficiently far to cause said arms to vibrate at their upper ends, and, through their link connections I, I with the sliding frame C, move the latter far enough (in the direction indicated by the arrow at Fig. 4), to place said frame C in the position indicated by the dotted lines at Fig. 4, or so that the mass of sand, located between the opposing faces of the plungers D, E, will be encompassed, laterally, by that portion of the device C which is provided with the top-plate l. The mass of sand will then be completely restrained within the envelope, formed laterally of the mass, by the top-plate l, and side-plates of the device C, and the top surface of the plate-like portion a of the main casting of the machine (from which the device C cannot rise, though it be free to slide longitudinally on said device a); and the two ends, so to speak, of the mass of sand will be opposed, or contacted by the two plungers D and E. The operator now causes the adjacent ends i, i, of the bell-cranks G, G to be depressed (through the medium of any suitable power multiplying mechanism, or devices, not shown, and by the application of foot power, or some other motor), to an extent sufficient to oscillate the bell-cranks G, G, on their fulcrums h, h, and thus move the piston rods b, b², in opposite directions, and so as to make the plungers D and E approach each other to the proper extent to sufficiently compress and solidify the mass of sand, and perfect the im-

pression, or impressions, therein of the pattern, or patterns secured to one, or both, of said plungers. Having thus completed the compression of the mold material, and perfected the mold, the operator; while the plungers remain, or are still held in the positions just ascribed to them, depresses the free end of hand-lever F, and thereby, through the devices connecting the rock shaft M, with the device C, slides the latter back to its original position; and, thence, farther back until it stands entirely clear of the completed sand mold. He then causes the adjacent ends i, i of the bell-cranks G, G, to be elevated to their original positions, or farther, which effectuates the complete disengagement of the patterns on the plungers from the sand mold, leaving the latter free to be lifted out of the machine. The removal of the finished mold, from the machine, is facilitated by the support of the plate H, since the plate may be easily lifted out of the machine and set to one side, with the sand mold resting on it. In practice I usually set the finished molds on a metallic, or stone, table made perfectly level, so that two, or more, molds can be placed properly face to face; and for this purpose, the hardened, button-like, projections z, are very useful, to properly support the molds, and also to stand the wear to which the points of support are subjected in sliding the molds along on the hard supporting table, or surface.

If the modified form of mold-sustaining plate, or device, seen at Fig. 5, be used, the side walls H², serve to support the opposite sides, or edges, of the finished mold, said side walls being tied together by the top-bar w, and under some conditions, as to the size and character of the mold, this modified form of device H may be preferable.

Of course, so far as the main features of my invention are concerned, either one, or more, patterns, or parts of a pattern, may be used on either one, or both, of the plungers, and if deemed expedient, one of the plungers might be a fixture (or stationary), while the other one might have all the motion necessary to do all the compressing of the mass, or charge necessary to the completion of the mold.

Such changes and others may be made without departing from the main features of novelty involved in my machine, and in practice, the main casting A should, of course, be provided with some suitable means of support, though none is shown in the drawings.

The particular detail construction shown, especially with reference to the two plungers moving in opposite directions; and the arrangement of the plate H, or its equivalent, with its button-like feet, I prefer; because it renders the machine well adapted to the purposes of carrying into effect a new way of making molds, or an improvement in the art of making molds, that I have invented, and which constitutes the subject matter of an

other application for Letters Patent by me, filed January 5, 1893, Serial No. 459,730, which, has no necessary connection with this case.

The forms and proportions of the parts may, of course, be varied, to suit the judgment of the machine builder, and according to the nature of the work to be done, and, where deemed expedient, several, duplicate, patterns may be secured to one plunger, and simultaneously impressed into one mass of the sand, or other mold material.

Having now so fully explained my improved molding machine that those skilled in the art can make and use the same, what I claim therein as new, and desire to secure by Letters Patent, is—

1. In a molding machine, the combination, with a suitable table-like surface, for supporting the sand, or other material, of which a mold is to be made; and two opposing surfaces, projecting from said table, one of which, at least, is movable, bodily thereon; of a sliding frame-like device, comprising two walls (which, with the aforesaid opposing surfaces and the said table-like surface constitute a receptacle for the sand, or other material), and having a partial top-plate; the whole constructed to operate in such manner that with the sliding frame-like device set in different positions, an open receptacle is formed to be filled in with the mold material, a closed receptacle is formed within which the material may be compressed to form the mold, and the completed mold is freed of all closely surrounding devices; in order that it may be removed from said table-like surface.

2. In a molding machine, the combination, with a main, body, portion, formed or provided, with a table-like device a, and perforated piston rod stands B, B; opposing platens, or plungers, D and E, arranged to move toward and from each other, and having their piston rods b and b² arranged in the said stands B, B; and the sliding frame-like device C, of means for simultaneously moving the plungers, in opposite directions, and mechanism by which the operator of the machine can set the sliding device C in different positions for the performance, respectively, of the operation of filling in the sand to be formed into a mold, compressing the same to complete the mold, and removing the finished mold from the machine.

3. The combination, with the sand-table a; a sliding frame-like device C arranged therein; and means for compressing the sand within the device C, of the removable mold-support H, adapted to operate as specified.

In witness whereof I have hereunto set my hand this 8th day of October, 1892.

GEORGE C. AVERY.

In presence of—

C. F. HUHLEIN,
J. A. GRAY.
